UNITED STATES PATENT OFFICE.

FREDERICK J. WEBER, OF CONNERSVILLE, INDIANA, ASSIGNOR TO THE STEEL STORAGE AND ELEVATOR CONSTRUCTION COMPANY, OF SAME PLACE.

ASH-CONVEYING APPARATUS.

SPECIFICATION forming part of Letters Patent No. 588,518, dated August 17, 1897.

Application filed May 5, 1897. Serial No. 635,260. (No model.)

To all whom it may concern:

Be it known that I, FREDERICK J. WEBER, of Connersville, Fayette county, Indiana, have invented certain new and useful Improvements in Ash-Conveying Apparatus, of which the following is a specification.

This invention pertains to pneumatic apparatus for conveying ashes from furnaces to more or less distant points of deposit; and the improvements will be readily understood from the following description, taken in connection with the accompanying drawings, in which—

Figure 1 is a front elevation of a building containing furnaces and equipped with ash-conveying apparatus exemplifying my invention, portions of the building appearing in vertical longitudinal section; Fig. 2, a plan of the furnaces and conveying apparatus, the building appearing in horizontal section; Fig. 3, a vertical transverse section through one of the receiving-hoppers of the apparatus; Fig. 4, a vertical section of the vacuum-chamber and its immediate connections, and Fig. 5 a horizontal section of that portion of the discharge-pipe below the vacuum-chamber.

In the drawings, 1 indicates the building; 2, a rank of furnaces therein which may be assumed as being ordinary boiler-furnaces; 3, a pipe disposed along in front of the rank 30 of furnaces but some distance below the deck or floor just in front of the furnaces; 4, the end of this pipe farthest away from the point of ultimate deposit for the ashes, the end in question being open to admit air freely to the pipe; 5, a hopper disposed in front of each furnace and having its base in communication with pipe 3, the top of the hoppers being flush with the floor in front of the furnaces; 6, a grating disposed at an intermediate point in the height of each hopper and of such fineness as to intercept clinkers or other material too heavy to be satisfactorily handled by an air-current; 7, a trap-door, one closing the top of each hopper; 8, a vacuum-chamber 45 having a hopper-bottom; 9, connection of pipe 3 with this vacuum-chamber at a point near the base thereof; 10, ash-discharge pipe, to be assumed as leading to the point at which the ashes are to be deposited by the apparatus; 50 11, pipe connection from the base of the vacuum-chamber downwardly into pipe 10,

this pipe connection 11 having an enlargement in the form of a cylindrical chamber with its axis horizontal; 12, a paddle-wheel disposed for rotation in such chamber and having its wings in neat engagement with the walls of the chamber, the chamber and paddle-wheel forming a feeder from the vacuum-chamber to pipe 10; 13, a second inlet-pipe to the vacuum-chamber, being merely an exemplifying duplication of pipe 9 for use in case the apparatus is to deal with ashes drawn through several pipes 3 instead of one such pipe, there being of course no opening at pipe 13 in case such additional pipe is not to be used; 14, an air-chamber, illustrated as being an ordinary rotary blower and exhauster operated by a direct-connected engine; 15, vacuum-pipe connecting the inlet side of the pump with the upper portion of the vacuum-chamber; 16, blast-pipe connecting the discharge side of the pump with pipe 10, pipe 10 being in effect merely a prolongation of pipe 16; 17, a horizontal widening of pipe 10 at the point where the feeder discharges into that pipe; 18, an angular divider disposed within the widened portion of pipe 10 and presenting its apex to the blast, which is thus split into two currents, one at each side of the divider, the currents later joining and going onward in pipe 10, the feeder delivering into pipe 10 at the base of the angular divider, and 19 exemplifying transmitting devices in the way of belts and pulleys, by means of which continuous rotary motion is given to the paddle-wheel of the feeder from the engine which drives the pump.

The pump being in operation, the result is the production of a partial vacuum in the vacuum-chamber, whereby there is caused a violent rush of air into the open end 4 of pipe 3 and through pipes 3 and 9 into the vacuum-chamber, the pump at the same time producing a violent blast of air through pipes 16 and 10, the blast-current being temporarily divided by divider 18, and there being at the base of the divider a region of relatively low air-pressure. One of trap-doors 7 being opened, it follows that there will be a violent rush of air downward through the grating 100 into pipe 3. Ashes being raked from the furnace into the open hopper become sucked into

pipe 3 and carried along therethrough and delivered into the vacuum-chamber. As the effect at the hopper is one of downward suction it follows that the handling of the ashes 5 in front of the furnaces would be practically free from dust. With pumping apparatus of sufficient capacity several of the trap-doors may be open at once, but the ordinary practice is to open one trap-door at a time.

10 The ashes received into the vacuum-chamber settle down therein by gravity and fill in succession the upper pockets of the paddle-wheel, which, in turning, carries those pockets downwardly and drops the ashes into the 15 broadened portion of pipe 10 at the base of the divider, the accumulation of ashes at the base of the receiver being acted on by the divided blast and swept thereby onwardly through pipe 10 to the point of deposit. Points 20 above and below the paddle-wheel represent, respectively, relatively low and high air-pres- 25 sures, these points being separated by the paddle-wheel, which acts as a cut-off and prevents the higher pressure reaching the vacuum-chamber, where it would interfere with the discharge from the vacuum-chamber and at the same time cut down the vacuum and increase the pumping duty.

The specific construction of feeder and di- 30 vider herein set forth is not claimed herein, such features forming the subject-matter of an application for patent filed May 5, 1897, Se- 35 rial No. 635,259.

I claim as my invention—

35 1. In an ash-conveying apparatus, the com- bination, substantially as set forth, of a hop- per in the floor near a furnace, a vacuum- chamber, a pipe leading from the base of said

hopper to the lower portion of said vacuum- chamber, a pump, a pipe from the upper por- 40 tion of said vacuum-chamber to the inlet side of said pump, a pipe leading from the dis- charge side of said pump to the point of de- 45 posit for the ashes, a pipe connection from the base of the vacuum-chamber to the last- mentioned pipe between said pump and said point of deposit, and a rotary feeder disposed in the last-mentioned pipe connection and serving to permit the downward movement of 45 ashes from the vacuum-chamber but to pre- 50 vent the upward passage of air from the dis- charge-pipe.

2. In an ash-conveying apparatus, the com- bination, substantially as set forth, of a se- 55 ries of hoppers disposed in the floor in front of a rank of furnaces, a trap-door for each hopper, a grating at each hopper, a vacuum- chamber, a pipe leading from the bases of all the hoppers to the lower portion of the vac- 60 uum-chamber, a pump, a pipe from the up- per portion of said vacuum-chamber to the inlet side of said pump, a pipe leading from the discharge side of said pump to the point of deposit for the ashes, a pipe connection from the base of the vacuum-chamber to the 65 last-mentioned pipe between said pump and said point of deposit, and a rotary feeder dis- 70 posed in the last-mentioned pipe connection and serving to permit the downward move- ment of ashes from the vacuum-chamber but to prevent the upward passage of air from the discharge-pipe.

FREDERICK J. WEBER.
